CARL H. ROTH, OF NEWARK, NEW JERSEY.

GRINDING AND POLISHING MACHINE.

1,297,596.

Specification of Letters Patent. Patented Mar. 18, 1919.

Application filed September 13, 1918. Serial No. 253,855.

To all whom it may concern:

Be it known that I, CARL H. ROTH, a subject of the Emperor of Germany, residing at Newark, in the county of Essex and State 5 of New Jersey, have invented certain new and useful Improvements in Grinding and Polishing Machines; and I do hereby declare the following to be a full, clear, and exact description of the invention, such as 10 will enable others skilled in the art to which it appertains to make and use the same, reference being had to the accompanying drawings, and to characters of reference marked thereon, which form a part of this specification. 15

The present invention has reference, generally, to improvements in machines used in the manufacture of cutlery; and the invention relates, more particularly, to a novel 20 automatic grinding and polishing machine for operating upon knife blades.

The invention has for its principal object to provide a machine for equally grinding at one and the same time both side surfaces 25 of the tang of a knife blade used in pocket-knives, so that proper parallel smooth opposite surfaces are formed on the tang of the knife-blade rendering the fit and smooth pivotal action of the same when assembled 30 with the pocket-knife handle assured.

Another object of the invention is to provide a machine which may be utilized either 35 for grinding, *i. e.* coarse abrading operations, or for polishing, *i. e.* fine abrading operations, according to the type of abrading wheel fitted to the machine.

Another object of the invention is to automatically control the separating movement of a pair of rotating abrading wheels 40 in conjunction with, and in proper timed relation to a work holding and feeding or positioning mechanism, the same operating to permit of a closing together of rotating wheels upon work inserted between the latter with sufficient pressure to secure the desired abrading effects.

A still further object of the invention is to provide a novel work holding and positioning means which automatically carries 50 to and withdraws from the abrading means the work to be operated upon.

Other objects of the present invention, not at this time more particularly enumerated,

will be clearly understood from the following detailed description of the same. 55

With the various objects of the present invention in view, the same consists, primarily, in the novel construction of grinding and polishing machine hereinafter set forth; and, the invention consists, furthermore, in the novel arrangements and combinations of the various devices and parts, as well as in the details of the construction of the same, all of which will be hereinafter more fully described, and then finally embodied in the claims appended hereto.

The invention is clearly illustrated in the accompanying drawings, in which:

Figure 1 is a plan view of the novel construction of machine made according to and embodying the principles of my present invention; Fig. 2 is a front elevation of the same; Fig. 3 is an end elevation of the same looking toward the right hand end of the machine; and Fig. 4 is a detail vertical cross section, taken on line 4-4 in Fig. 1, and drawn on an enlarged scale.

Similar characters of reference are employed in all of the hereinabove described views, to indicate corresponding parts. 80

Referring now to the said drawings the reference character 1 indicates a suitable supporting bed-frame upon which the mechanism is mounted. Secured upon said bed-frame 1, adjacent to one end thereof, is a longitudinally adjustable bed-plate 2 having a longitudinal guide channel 3 in its upper surface. Arranged in said guide channel 3 is a slide-member 4 capable of longitudinal adjusting movement. Projecting upwardly from said slide-member 4 are a pair of longitudinally spaced pedestal bearings 5 in which is journaled a spindle 6, upon the inward end of which is fixed a supporting disk 7, to the face of which is 95 suitably secured an abrading wheel 8. Fixed upon said spindle 6, preferably in a position disposed between said pedestal bearings 5 is a belt-pulley 9 over which a power transmission belt (not shown) may be run to 100 impart a rotary movement to said spindle and supporting disk, and consequently to the abrading wheel attached to the latter.

Secured upon said bed-frame 1, adjacent to the opposite end thereof, is a longitudinally adjustable bed-plate 10 having a lon- 105

itudinal guide channel 11 in its upper surface. Arranged in said guide channel 11 is a slide-member 12 capable of reciprocatory longitudinal movement. Projecting upwardly from said slide-member 12 are a pair of pedestal bearings 13 in which is journaled a spindle 14, upon the inward end of which is fixed a supporting disk 15, to the face of which is suitably secured an abrading wheel 16. Fixed on said spindle 14, preferably in a position disposed between said pedestal bearings 13, is a belt pulley 17 over which a power transmission belt (not shown) may be run to impart a rotary movement to said spindle and supporting disk, and consequently to the abrading wheel attached to the latter.

As thus mounted and disposed the said abrading wheels 8 and 16 have their outer side faces opposed to each other, and slightly spaced apart.

Connected with said bed-plate 10 are a pair of outwardly and laterally projecting bracket-portions 18. Secured upon said bracket-portions 18, adjacent to the outer free ends thereof, are longitudinally aligned bearing pedestals 19 in which is journaled a driving shaft 20. Said driving shaft 20 is provided with a fast pulley 21 and a loose pulley 22 with which a driving belt, (not shown), may be associated for driving said shaft 20. Fixed on said shaft 20 is a driving gear 23. Also secured upon said bracket-portions 18 are a second pair of longitudinally aligned bearing pedestals 24 in which is journaled a lay or counter-shaft 25. Fixed upon said counter-shaft 25 is a large gear 26 which meshes with said driving gear 23, so that the rotary movement of the driving shaft is transmitted to said counter-shaft at a properly reduced speed. Fixed upon the inward end of said counter shaft 25 is a crank-wheel 27, and fixed upon the outward end of said counter-shaft 25 is a cam-wheel 28 provided with adjustable cam-plates 29 on its inner face.

Secured in a central position upon the front side of said bed-frame 1 are a pair of parallel laterally projecting bracket-members 30, each having at their inner ends an upwardly projecting standard 31 provided with a socket-portion 32 at its free end, and each having at their outer ends an upwardly projecting arm 33 terminating in a socket-portion 34 aligned with the opposite socket-portions 32 of the standards 31. Secured in said socket-portions 32 and 34, so as to extend therebetween, are parallel guide-rods 35. Mounted upon said parallel guide-rods 35, so as to slide back and forth thereon is a reciprocating carriage-member 36, provided at its outer lower end with a transverse wrist-pin 37. Connected with the outer ends of said bracket-members 30 are

a pair of bearing-members 38 in which is mounted a rock-shaft 39, having a rocking-arm 40 fixed thereon, and positioned between the said bearing-members 38. A connecting-rod 41 interconnecting the free end of said rocking-arm 40 which the wrist-pin 37 of said carriage member 36 translates the rocking movement of said rock-shaft and rocking-arm into a reciprocating sliding movement which is transmitted to said carriage-member 36. The means for rocking said rock-shaft comprises a second rocking-arm 42 fixed thereon, the free end of which is operatively connected with said crank-wheel 27 of the counter-shaft 25 by means of a suitable connecting-rod 43. The said carriage-member 36, as thus mounted and operated, is positioned in alignment with the opposed faces of said abrading wheels 8 and 16. Rotatably mounted in connection with said carriage-member 36 is a spindle 44 provided at its forward end with a cradle-portion 45 constructed to hold a knife-blade 46, so that the sides of the tang 47 of the latter are exposed to the action of said opposed abrading wheels 8 and 16 at proper times. Said cradle portion 45 is provided with a stop-post 48 at its free end against which said tang 47 abuts, and is further provided with side-guards 49 for engaging the sides of the blade 46 to hold the same edgewise in supported relation upon said cradle-portion. Journaled in said carriage-member 36, so as to be positioned beneath said spindle 44 is a transverse spindle 50 having fixed thereon a wheel or drum 51. Said spindle 44 is also provided with a small wheel or pulley 52. Secured to the circumference of said wheel or drum 51 is a pull strap 53, which passes around under the wheel or drum 51, and thence upwardly over the wheel or pulley 52 of said spindle 44 to the circumference of which the opposite end of said pull strap 53 is secured. Fixed upon an outwardly projecting end of said transverse spindle 50 is a trip-arm 54 having an anti-friction roller 55 mounted on its free end. Projecting from the forward end of said carriage-member 36 is a stop-pin 56, and projecting outwardly and laterally from the side of said cradle-portion 45 is a stop-arm 57 which normally engages said stop-pin 56 to determine the normal carrying position of said cradle-portion 45. Coiled around said spindle 44 is a spring-member 58, one end of which is anchored to a portion of said carriage-member 36, and the opposite end of which is anchored or fixed to said spindle 44. The tension of said spring-member 58 tends to so rotate said spindle 44 and its cradle-portion 45, as to carry the stop-arm 57 into engagement with said stop-pin 56, and to normally retain the same in such engagement, thereby normally

holding the cradle-portion in upright blade carrying position. Fixed upon the side of one of said bracket-members 30, so as to project upwardly therefrom, in the path of said trip-arm 54 and its anti-friction roller 55, is a trip-cam 59, and secured in like manner to said bracket-member 30, in the rear of said trip-cam 59 is a stop-projection 60. The operation of the blade carrying 10 means is, briefly, as follows:—

The carriage-member 36 is reciprocated by its above described transmission mechanism. When the carriage-member 36 is in its retracted position, the operator inserts a 15 knife-blade 46 in the cradle-portion 45, with the tang 47 of the blade forwardly presented. As the carriage-member 36 is slid forward on the guide-rods 35 the tang 47 is carried between the opposed faces of the abrading 20 wheels 8 and 16, and held in position to be operated upon in the manner subsequently to be described. After the opposite sides of the tang 47 has been ground by the opposed faces of the abrading wheels, the carriage- 25 member is retracted to withdraw the blade 46 from between said abrading wheels. As the carriage-member is thus moved backward upon the guide-rods 35, the trip-arm 54 is carried past the trip-cam 59, so that its 30 anti-friction roller 55 engages the latter, and in passing over the same causes the trip-arm to be swung forward and upwardly. The upward swinging of said trip-arm rotates or rocks said transverse spindle 35 50 and its wheel or drum 51, the latter by such rotation winding up upon itself the pull-strap 53, which is thereby given a downward pull. This downward pull of the pull-strap, by reason of its connection 40 with the wheel or pulley 52 of the spindle 44, tends to rotate the latter imparting to the same a half turn, which turns upside-down the cradle-portion 45, thereby permitting the ground blade 46 to drop out of the 45 cradle-portion into a suitable receiving receptacle. As the trip-arm flings away from the trip-cam 59, its opposite swinging momentum is arrested by the engagement of its anti-friction roller 55 with the 50 stop-projection 60 so that a too sudden movement thereof has no tendency to disarrange the pull-strap 53 from proper relation to the respective wheels 51 and 52. The 55 rotation of the spindle 44, for the purpose and in the manner above described tends to wind up and therefore increase the tension of said spring-member 58, so that when the trip-arm 54 is released from the trip-cam 59, the tension of the spring-member 60 will cause a reverse or return rotation of the spindle 44, and through the opposite pulling of the pull strap 53, a consequent reverse or return rotation of the transverse spindle 50, which returns all parts to normal initial

position, and again positions said cradle-portion 45 ready to receive another knife-blade 46, to be carried forward between the abrading wheels 8 and 16 by the forward reciprocation of the carriage-member 36. It may be mentioned that, as the carriage-member 36 moves forward, the trip-arm and its anti-friction roller will pass over the trip-cam, but since the motion is reversed no turning effect is imparted to the spindle 44, as the opposite or reverse rotation of the transverse spindle 50 and its wheel or drum 51 merely results in slackening the pull-strap 53, as will be understood.

The said abrading wheels 8 and 16 are initially positioned so that their opposed faces are abnormally separated in such a manner that the tang 47 of the knife-blade 46 may be easily carried therebetween. The abrading wheel 8 and its supporting and transmission mechanism has a normal fixed 80 or stationary position, while the abrading wheel 16 and its supporting and transmission mechanism is mounted to be capable of movement at proper times toward said fixed abrading wheel 8. The movement of said 85 abrading wheel 16 toward the abrading wheel 8 is effected by a pull-spring 61, one end of which is anchored upon a post 62 fixed in said bed-plate 10, and its opposite 90 end anchored upon a post 63 fixed in a convenient part of the reciprocating supporting means for said abrading-wheel and its spindle. The tension of said pull-spring 61 tends to pull said slide-member 12 forward 95 in the guide-channel 11. The means for 100 controlling the movement of said abrading-wheel 16 toward the abrading wheel 8, consists in a lever member 64 fulcrumed on a bracket-shelf 65 connected with said bed-plate 10. One end of said lever member 64 105 is interconnected with said slide-member 12 by means of a connecting-link 66, while the opposite end of said lever-member 64 is provided with an anti-friction roller 67 which rides operatively upon said cam-wheel 28 110 and its cam-plates 29. The action of said cam-wheel upon the lever-member is timed with relation to the movement of said carriage-member 36, so that as the latter is retracted, the cam-wheel's rotation carries a 115 cam-plate 29 into engagement with the roller end of the lever member 64, thereby causing a rocking movement of the latter tending to pull upon the connecting link 66, and consequently retracting the slide-member 120 120 against the tension of the pull-spring 61, and thereby withdrawing or separating said abrading-wheel 16 from the abrading wheel 8, so that a knife-blade 46 may be easily withdrawn from between the said abrading-wheels. As the carriage-member 36 moves forward, carrying another knife-blade in its cradle-portion 45, the abrading

wheels are maintained in separated relation until the tang 47 partially enters between the same, whereupon the rotation of the cam-wheel 28 carries the cam-plate 29 away from the roller end of the lever-member 64, allowing the latter to drop against the lower face of the cam-wheel, thus permitting an opposite swing of the lever-member, as the pull-spring 61 is thus freed to pull forward the slide-member 12 and the abrading wheel 16 and its supporting mechanism carried thereby, so that said abrading-wheel 16 closes upon the tang 47 and not only grinds the adjacent face thereof but also presses the opposite face thereof into operative relation with the abrading wheel 8. This operative relation of the abrading wheels 8 and 16 to the tang 47 is continued until the latter is carried completely forward, whereupon the carriage-member begins its retracted movement, and the rotation of the cam-wheel 28 again carries a cam-plate 29 into swinging engagement with said lever-member 64 to again retract the abrading-wheel 16 as already above described. It will be noted that the movement of the carriage-member and its cradle portion, and the opening and closing movement of said abrading wheels are relatively timed since each mechanism is properly controlled by the rotation of the counter-shaft as driven from the main driving shaft. It will also be understood that the abrading wheels are both driven at high speed at all times by the pulleys of their respective spindles, and independently of the operation of the driving shaft 20 and counter shaft 25.

Since the thickness of the tangs of different sizes of knife-blades varies, it is desirable to provide means for adjusting the abrading wheels 8 and 16, as to their initial positions, relative to the work to be done. To this end the fixed or stationary abrading-wheel may be properly positioned by moving the slide-member 4 in the guide-channel 3 of the bed-plate 2, in the direction desired, this being accomplished by means of an adjusting screw 68, which turns in a stationary nut 69 fixed on the end of the bed-frame 1, the end of said screw being secured to said slide-member 4 by means of a coupling lug 70, projecting from the latter, and the collars 71 fixed to said screw on either side of said coupling lug, so that while said screw is free to turn, its longitudinal movement will nevertheless be imparted to said slide-member 4. The reciprocating abrading wheel 16 and its controlling mechanism, may be properly positioned by moving the bed-plate 10 upon the bed-frame 1, in the direction desired this being accomplished by means of an adjusting screw 72, which turns in a nut-piece 73 depending from an integral part of said bed-plate 10, preferably

the bracket shelf 65, the end of the screw 65 being rotatably secured in a fixed coupling 74 secured upon the end of said bed-frame 1, so that as the screw is turned the nut-piece 73 is caused to travel thereon in the desired direction, and consequently imparts the desired movement to said bed-plate 10 and the mechanism supported upon and associated therewith. The bed-plate 10 when adjusted as desired may be locked to said bed-frame 1 in rigidly secured relation thereto by means of the bolts 75. Slots 76, formed in said bed-plate 10, through which said bolts 75 extend permit the necessary longitudinal adjusting movements of said bed-plate relative to the bed-frame. 80

Of course it will be understood that the means for adjusting the position of the abrading wheels is subject to more or less wide variation as to mechanical means and details of construction, and therefore, the means above described is deemed merely illustrative, and I do not necessarily limit myself to its particular use. 85

It will also be understood that the machine may be equipped with various kinds of abrading wheels according to the kind of work desired to be done. For coarse grinding carborundum or emery wheels may be used in various degrees of grain, and for the finer abrading effects, such as in polishing, 95 cloth, buckskin or any other suitable wheel may be used; the operation of the machine being essentially the same with all types of abrading wheels.

I am aware that some changes may be 100 made in the several arrangements and combinations of the various devices and parts, as well as in the details of the construction of the same, without departing from the scope of the present invention, as above described, and as defined in the appended claims. Hence, I do not limit the present invention to the exact arrangements and combinations of the various devices and parts as set forth in the above specification, 110 nor do I confine myself to the exact details of the construction of the said parts as illustrated in the accompanying drawings. 105

I claim:—

1. In a machine of the kind described, a 115 pair of abrading wheels disposed to mutually oppose their operative faces, means for rotatably mounting one of said abrading wheels in a fixed position, means for rotatably mounting the other of said abrading 120 wheels for axial, reciprocable movement toward and away from said fixed abrading wheel to mutually separate said wheels for the reception of work therebetween, a lever means interconnected at one end with the 125 mounting of said movable wheel, a cam-wheel for operatively engaging the opposite end of said lever means for oscillating the

same to govern the reciprocable movement of said movable wheel, spring means for moving and holding said movable wheel in operative relation to said fixed wheel as governed by the operation of said lever means, transmission means from which said cam-wheel is driven, a reciprocable work supporting means adapted to carry the work between and in operative relation to said 10 abrading wheels, and means for reciprocating said work supporting means in timed relation to the separating movement of said abrading wheels.

2. In a machine of the kind described, a pair of abrading wheels disposed to mutually oppose their operative faces, means for rotatably mounting one of said abrading wheels in a fixed position, means for rotatably mounting the other of said abrading 20 wheels for axial reciprocable movement toward and away from said fixed abrading wheel to mutually separate said wheels for the reception of work therebetween, a lever means interconnected at one end with the mounting of said movable wheel, a cam-wheel for operatively engaging the opposite end of said lever means for oscillating the same to govern the reciprocable movement of said movable wheel, spring means for moving and holding said movable wheel in operative relation to said fixed wheel as governed by the operation of said lever means, transmission means from which said cam-wheel is driven, a reciprocable carriage-member, guide means for slidably supporting said carriage-member, a rock-shaft having a rocking-arm, a connecting-rod interconnecting said carriage-member with said rocking-arm, means operated from said 35 transmission means for oscillating said rock-shaft, and a work supporting cradle carried by said carriage-member for introducing the work between and in operative relation to said abrading wheels.

3. In a machine of the kind described, a pair of abrading wheels disposed to mutually oppose their operative faces, means for rotatably mounting one of said abrading wheels in a fixed position, means for rotatably mounting the other of said abrading 50 wheels for axial reciprocable movement toward and away from said fixed abrading wheel to mutually separate said wheels for the reception of work therebetween, a lever means interconnected at one end with the mounting of said movable wheel, a cam-wheel for operatively engaging the opposite end of said lever means for oscillating the same to govern the reciprocable movement of said movable wheel, spring means for moving and holding said movable wheel in operative relation to said fixed wheel as governed by the operation of said lever means, transmission means from which said

cam-wheel is driven, a reciprocable carriage-member, guide means for slidably supporting said carriage-member, a rock-shaft having a rocking-arm, a connecting-rod interconnecting said carriage-member with said rocking-arm, means operated from said transmission means for oscillating said rock-shaft, a spindle journaled in said carriage-member, a work supporting cradle secured to the forward end of said spindle, and means operating upon the retraction of said carriage-member to rotate said spindle for upsetting said cradle to dislodge the finished work therefrom.

4. In a machine of the kind described, a pair of abrading wheels disposed to mutually oppose their operative faces, means for rotatably mounting one of said abrading wheels in a fixed position, means for rotatably mounting the other of said abrading 80 wheels for axial reciprocable movement toward and away from said fixed abrading wheel to mutually separate said wheels for the reception of work therebetween, a lever means interconnected at one end with the mounting of said movable wheel, a cam-wheel for operatively engaging the opposite end of said lever means for oscillating the same to govern the reciprocable movement of said movable wheel, spring means for moving and holding said movable wheel in 85 operative relation to said fixed wheel as governed by the operation of said lever means, transmission means from which said cam-wheel is driven, a reciprocable carriage-member, guide means for slidably supporting said carriage-member, a rock-shaft having a rocking-arm, a connecting-rod interconnecting said carriage-member with said 90 rocking-arm, means operated from said transmission means for oscillating said rock-shaft, a spindle journaled in said carriage-member, a work supporting cradle secured to the forward end of said spindle, and means operating upon the retraction of said carriage-member to rotate said spindle for upsetting said cradle to dislodge the finished work 95 therefrom, comprising a transverse spindle journaled in said carriage-member having a drum mounted thereon, a wheel on said first mentioned spindle, a pull-strap anchored upon said drum and having its opposite end secured to said wheel, a trip-arm secured to said transverse spindle, a trip-cam with which said trip-arm engages upon the retraction of said carriage-member, spring means engaged with said first mentioned spindle to return the same to normal position, and stop means for determining the normal position of said spindle and its cradle.

5. In a machine of the kind described, a bed-frame, a bed-plate having a longitudinal guide channel fixed adjacent to one end of

- said bed-frame, a slide-plate mounted in said channel having a pair of bearing pedestals projecting upwardly therefrom, a spindle journaled in said bearing pedestals, a pulley on said spindle for rotating the same, a fixed abrading wheel fixed on the inner end of said spindle, means for adjusting said slide-plate to determine the fixed position of said abrading wheel, a second bed-plate having a 5 longitudinal guide-channel mounted on said bed-frame adjacent to its opposite end, a second slide-plate longitudinally reciprocable in said guide-channel having a pair of bearing pedestals projecting upwardly therefrom, a second spindle journaled in said bearing pedestals in axial alinement with said first mentioned spindle, a pulley on said second spindle for rotating the same, a movable abrading-wheel on the inner end of said 10 second spindle having its operative face opposed to the operative face of said fixed abrading wheel, spring-means engaging said second slide-plate to draw the same forward to position said movable abrading wheel in operative relation to said fixed abrading wheel, means for adjusting said second bed-plate to determine the operative spaced relation of said movable abrading wheel from said fixed abrading wheel, automatic means 15 for retracting said second slide-plate to abnormally separate said movable abrading wheel from said fixed abrading wheel to permit the insertion of work therebetween, a reciprocable work supporting means operating in timed relation to the movements of said movable abrading wheel adapted to automatically carry to and from operative relation to said abrading wheels the work to be done.
6. In a machine of the kind described, a bed-frame, a bed-plate having a longitudinal guide-channel fixed adjacent to one end of said bed-frame, a slide-plate mounted in said channel having a pair of bearing pedestals projecting upwardly therefrom, a spindle journaled in said bearing pedestals, a pulley on said spindle for rotating the same, a fixed abrading wheel fixed on the inner end of said spindle, means for adjusting said slide-plate to determine the fixed position of said abrading wheel, a second bed-plate having a longitudinal guide-channel mounted on said bed-frame adjacent to its opposite end, a second slide-plate longitudinally reciprocable in said guide-channel having a pair of bearing pedestals projecting upwardly therefrom, a second spindle journaled in said bearing pedestals in axial alinement with said first mentioned spindle, a pulley on said second spindle for rotating the same, a movable abrading-wheel on the inner end of said second spindle having its operative face opposed to the operative face of said fixed abrading wheel, spring-means engaging said second slide-plate to draw the same forward to position said movable abrading wheel in operative relation to said fixed abrading wheel, means for adjusting said second bed-plate to determine the operative spaced relation of said movable abrading wheel from said fixed abrading wheel, a pivoted lever mounted in connection with said second bed-plate, a link means interconnecting said second slide-plate with one end of said lever, a lay-shaft, means for mounting said lay-shaft, a cam-wheel operated by said lay-shaft and engaging the opposite end of said lever to swing the same to cause the retraction of said second slide-plate to draw the same forward to position said movable abrading wheel in operative relation to said fixed abrading wheel, means for adjusting said second bed-plate to determine the operative spaced relation of said movable abrading wheel from said fixed abrading wheel, a pivoted lever mounted in connection with said second bed-plate, a link means interconnecting said second slide-plate with one end of said lever, a lay-shaft, means for mounting said lay-shaft, a cam-wheel operated by said lay-shaft and engaging the opposite end of said lever to swing the same to cause the retraction of said second slide-plate for abnormally separating said movable abrading wheel from said fixed abrading wheel, means for driving said lay-shaft, a reciprocable work supporting means operating in timed relation to the movements of said movable abrading wheel adapted to automatically carry to and from operative relation to said abrading wheels the work to be done.
7. In a machine of the kind described, a bed-frame, a bed-plate having a longitudinal guide-channel fixed adjacent to one end of said bed-frame, a slide-plate mounted in said channel having a pair of bearing pedestals projecting upwardly therefrom, a spindle journaled in said bearing pedestals, a pulley on said spindle for rotating the same, a fixed abrading wheel fixed on the inner end of said spindle, means for adjusting said slide-plate to determine the fixed position of said abrading wheel, a second bed-plate having a longitudinal guide-channel mounted on said bed-frame adjacent to its opposite end, a second slide-plate longitudinally reciprocable in said guide-channel having a pair of bearing pedestals projecting upwardly therefrom, a second spindle journaled in said bearing pedestals in axial alinement with said first mentioned spindle, a pulley on said second spindle for rotating the same, a movable abrading-wheel on the inner end of said second spindle having its operative face opposed to the operative face of said fixed abrading wheel, spring-means engaging said second slide-plate to draw the same forward to position said movable abrading wheel in operative relation to said fixed abrading wheel, means for adjusting said second bed-plate to determine the operative spaced relation of said movable abrading wheel from said fixed abrading wheel, a pivoted lever mounted in connection with said second bed-plate, a link means interconnecting said second slide-plate with one end of said lever, a lay-shaft, means for mounting said lay-shaft, a cam-wheel operated by said lay-shaft and engaging the opposite end of said lever to swing the same to cause the retraction of said second slide-plate to draw the same forward to position said movable abrading wheel in operative relation to said fixed abrading wheel, means for adjusting said second bed-plate to determine the operative spaced relation of said movable abrading wheel from said fixed abrading wheel, a pivoted lever mounted in connection with said second bed-plate, a link means interconnecting said second slide-plate with one end of said lever, a lay-shaft, means for mounting said lay-shaft, a cam-wheel operated by said lay-shaft and engaging the opposite end of said lever to swing the same to cause the retraction of said second slide-plate for abnormally separating said movable abrading wheel from said fixed abrading wheel, means for driving said lay-shaft, a reciprocable work supporting means operating in timed relation to the movements of said movable abrading wheel adapted to automatically carry to and from operative relation to said abrading wheels the work to be done.

plate for abnormally separating said movable abrading wheel from said fixed abrading-wheel, means for driving said lay-shaft, a reciprocable carriage-member, guide-means projecting laterally from said bed-frame for slidably supporting said carriage-member, a rock-shaft having a rocking arm journaled at the outer end of said guide means, a connecting-rod interconnecting 5 said carriage-member with said rock-shaft, a crank-wheel on said lay-shaft, a second rocking-arm on said rock-shaft, a connecting-rod interconnecting said crank-wheel with said second rocking-arm, a spindle journaled in said carriage-member, a work supporting cradle secured to the forward end of said spindle, and means operating 10 upon the retraction of said carriage-member to rotate said spindle for upsetting said cradle to dislodge the finished work therefrom.

8. In a machine of the kind described, a bed-frame, a bed-plate having a longitudinal guide-channel fixed adjacent to one end of said bed-frame, a slide-plate mounted in said channel having a pair of bearing pedestals projecting upwardly therefrom, a spindle journaled in said bearing pedestals, a 20 pulley on said spindle for rotating the same, a fixed abrading wheel fixed on the inner end of said spindle, means for adjusting said slide-plate to determine the fixed position of said abrading wheel, a second bed-plate having a longitudinal guide-channel mounted on said bed-frame adjacent to its opposite end, a second slide-plate longitudinally reciprocable in said guide-channel having 25 a pair of bearing pedestals projecting upwardly therefrom, a second spindle journaled in said bearing pedestals in axial alignment with said first mentioned spindle, a pulley on said second spindle for rotating 30 the same, a movable abrading-wheel on the inner end of said second spindle having its operative face opposed to the operative face of said fixed abrading wheel, spring-means engaging said second slide-plate to draw the 35 same forward to position said movable abrading wheel in operative relation to said fixed abrading wheel, means for adjusting said second bed-plate to determine the operative spaced relation of said movable abrading 40 wheel from said fixed abrading wheel, a pivoted lever mounted in connection with said second bed-plate, a link means interconnecting said second slide-plate with one 45 end of said lever, a lay-shaft, means for mounting said lay-shaft, a cam-wheel operated by said lay-shaft and engaging the opposite end of said lever to swing the same to cause the retraction of said second slide-plate for abnormally separating said movable abrading wheel from said fixed abrading-wheel, means for driving said lay-shaft, a reciprocable carriage-member, guide-means projecting laterally 50 from said bed-frame for slidably supporting said carriage-member, a rock-shaft having a rocking arm journaled at the outer end of said guide means, a connecting-rod inter-

member, a rock-shaft having a rocking arm 65 journaled at the outer end of said guide means, a connecting-rod interconnecting said carriage-member with said rocking-arm, a crank-wheel on said lay-shaft, a second 70 rocking-arm on said rock-shaft, a connecting-rod interconnecting said crank-wheel with said second rocking-arm, a spindle journaled in said carriage-member, a work supporting cradle secured to the forward end of said spindle, and means operating 75 upon the retraction of said carriage-member to rotate said spindle for upsetting said cradle to dislodge the finished work therefrom.

9. In a machine of the kind described, a bed-frame, a bed-plate having a longitudinal guide-channel fixed adjacent to one end of said bed-frame, a slide-plate mounted in said channel having a pair of bearing pedestals projecting upwardly therefrom, a spindle 80 journaled in said bearing pedestals, a pulley on said spindle for rotating the same, a fixed abrading wheel fixed on the inner end of said spindle, means for adjusting said slide-plate to determine the fixed position 85 of said abrading wheel, a second bed-plate having a longitudinal guide-channel mounted on said bed-frame adjacent to its opposite end, a second slide-plate longitudinally reciprocable in said guide-channel having 90 a pair of bearing pedestals projecting upwardly therefrom, a second spindle journaled in said bearing pedestals in axial alignment with said first mentioned spindle, a pulley on said second spindle for rotating 95 the same, a movable abrading-wheel on the inner end of said second spindle having its operative face opposed to the operative face of said fixed abrading wheel, spring-means engaging said second slide-plate to draw the 100 same forward to position said movable abrading wheel in operative relation to said fixed abrading wheel, means for adjusting said second bed-plate to determine the operative spaced relation of said movable 105 abrading wheel from said fixed abrading wheel, a pivoted lever mounted in connection with said second bed-plate, a link means interconnecting said second slide-plate with one end of said lever, a lay-shaft, 110 means for mounting said lay-shaft, a cam-wheel operated by said lay-shaft and engaging the opposite end of said lever to swing the same to cause the retraction of 115 said second slide-plate for abnormally separating said movable abrading wheel from said fixed abrading-wheel, means for driving said lay-shaft, a reciprocable carriage-member, guide-means projecting laterally 120 from said bed-frame for slidably supporting said carriage-member, a rock-shaft having a rocking arm journaled at the outer end of said guide means, a connecting-rod inter-

- connecting said carriage-member with said rocking-arm, a crank-wheel on said lay-shaft, a second rocking-arm on said rock-shaft, a connecting-rod interconnecting said 5 crank-wheel with said second rocking-arm, a spindle journaled in said carriage-member, a work supporting cradle secured to the forward end of said spindle, and means operating upon the retraction of said carriage-member to 10 rotate said spindle for upsetting said cradle to dislodge the finished work therefrom, comprising a transverse spindle journaled in said carriage-member having a drum mounted thereon, a wheel on said first mentioned spindle a pull-strap anchored upon said drum and having its opposite end secured to said wheel, a trip-arm secured to said transverse spindle, a trip-cam with which said trip-arm engages upon the retraction 15 of said carriage-member, spring means engaged with said first mentioned spindle to return the same to normal position, and stop means for determining the normal position of said spindle and its cradle.
- 25 10. In a machine of the kind described, a bed-frame, a fixed rotatable abrading wheel, means for mounting said fixed abrading wheel on said bed-frame, a rotatable movable abrading wheel having its operative 30 face opposed to the operative face of said fixed abrading wheel, means for mounting said movable abrading wheel on said bed-frame for reciprocal axial movement thereon, spring means for holding and returning said movable abrading wheel to operative 35 relation with said fixed abrading wheel, automatic means for retracting said movable abrading wheel to abnormally separate the same from said fixed abrading 40 wheel to permit the insertion of work therebetween, a reciprocal work supporting means operating in timed relation to the movements of said movable abrading wheel adapted to automatically carry to and from 45 operative relation to said abrading wheel the work to be done.
11. In a machine of the kind described, a bed-frame, a fixed rotatable abrading wheel, means for mounting said fixed abrading 50 wheel on said bed-frame, a rotatable movable abrading wheel having its operative face opposed to the operative face of said fixed abrading wheel, means for mounting said movable abrading wheel on said bed-frame 55 for reciprocal axial movement thereon, spring means for holding and returning said movable abrading wheel to operative relation with said fixed abrading wheel, a pivoted lever, a link means interconnecting one end 60 of said lever with the mounting of said movable abrading wheel, a lay-shaft, means for mounting said lay-shaft, a transmission means for driving said lay-shaft, a cam-wheel operated by said lay-shaft and engag- 65 ing the opposite end of said pivoted lever to swing the same to cause the abnormal separation of said movable abrading wheel from said fixed abrading-wheel, a reciprocable work supporting means operating in timed relation to the movements of said movable 70 abrading wheel adapted to automatically carry to and from operative relation to said abrading wheels the work to be done.
12. In a machine of the kind described, a bed-frame, a fixed rotatable abrading wheel, 75 means for mounting said fixed abrading wheel on said bed-frame, a rotatable movable abrading wheel having its operative face opposed to the operative face of said fixed abrading wheel, means for mounting 80 said movable abrading wheel on said bed-frame for reciprocal axial movement thereon, spring means for holding and returning said movable abrading wheel to operative 85 relation with said fixed abrading wheel, a pivoted lever, a link means interconnecting one end of said lever with the mounting of said movable abrading wheel, a lay-shaft, means for mounting said lay-shaft, a transmission 90 means for driving said lay-shaft, a cam-wheel operated by said lay-shaft and engaging the opposite end of said pivoted lever to swing the same to cause the abnormal separation of said movable abrading wheel from said fixed abrading-wheel, a reciprocable 95 carriage-member, guide-means projecting laterally from said bed-frame for slidably supporting said carriage-member, a rock-shaft having a rocking-arm journaled at the outer end of said guide-means, a connecting rod interconnecting said carriage-member with said rocking-arm, a crank-wheel on said lay-shaft, a second rocking-arm on said rock-shaft, a connecting rod interconnecting said crank-wheel with said second rocking-arm, and a work supporting 100 cradle carried by said carriage member for introducing the work between and in operative relation to said abrading wheels.
13. In a machine of the kind described, a 105 bed-frame, a fixed rotatable abrading wheel, means for mounting said fixed abrading wheel on said bed-frame, a rotatable movable abrading wheel having its operative face opposed to the operative face of said fixed abrading wheel, means for mounting said 110 movable abrading wheel on said bed-frame for reciprocal axial movement thereon, spring means for holding and returning said movable abrading wheel to operative 115 relation with said fixed abrading wheel, a pivoted lever, a link means interconnecting one end of said lever with the mounting of said movable abrading wheel, a lay-shaft, means for mounting said lay-shaft, a transmission 120 means for driving said lay-shaft, a cam-wheel operated by said lay-shaft and engaging the opposite end of said pivoted lever to swing the same to cause the abnormal separation of said movable abrading wheel from said fixed abrading-wheel, a reciprocable 125 carriage-member, guide-means projecting laterally from said bed-frame for slidably supporting said carriage-member, a rock-shaft having a rocking-arm journaled at the outer end of said guide-means, a connecting rod interconnecting said carriage-member with said rocking-arm, a crank-wheel on said lay-shaft, a second rocking-arm on said rock-shaft, a connecting rod interconnecting said crank-wheel with said second rocking-arm, and a work supporting cradle carried by said carriage member for introducing the work between and in operative relation to said abrading wheels.

to swing the same to cause the abnormal separation of said movable abrading wheel from said fixed abrading-wheel, a reciprocable carriage-member, guide-means projecting laterally from said bed-frame for slidably supporting said carriage-member, a rock-shaft having a rocking-arm journaled at the outer end of said guide-means, a connecting rod interconnecting said carriage-member with said rocking-arm, a crank-wheel on said lay-shaft, a second rocking-arm on said rock-shaft, a connecting rod interconnecting said crank-wheel with said second rocking-arm, a spindle journaled in 10 said carriage-member, a work supporting cradle secured to the forward end of said spindle, and means operating upon the retraction of said carriage-member to rotate said spindle for upsetting said cradle to dislodge the finished work therefrom.

14. In a machine of the kind described, a bed-frame, a fixed rotatable abrading wheel, means for mounting said fixed abrading wheel on said bed-frame, a rotatable movable abrading wheel having its operative face opposed to the operative face of said fixed abrading wheel, means for mounting said movable abrading wheel on said bed-frame for reciprocable axial movement thereon, 25 spring means for holding and returning said movable abrading wheel to operative relation with said fixed abrading wheel, a pivoted lever, a link means interconnecting one end of said lever with the mounting of said movable abrading wheel, a lay-shaft, means for mounting said lay-shaft, a transmission means for driving said lay-shaft, a cam-wheel operated by said lay-shaft and engaging the opposite end of said pivoted lever 30 40 to swing the same to cause the abnormal separation of said movable abrading wheel from said fixed abrading-wheel, a reciprocable carriage-member, guide-means projecting laterally from said bed-frame for slidably supporting said carriage-member, a rock-shaft having a rocking-arm journaled at the outer end of said guide-means, a connecting rod interconnecting said carriage-member with said rocking-arm, a crank-wheel on said lay-shaft, a second rocking-arm on said rock-shaft, a connecting rod interconnecting said crank-wheel with said second rocking-arm, a spindle journaled in 45 said carriage-member, a work supporting cradle secured to the forward end of said spindle, and means operating upon the retraction of said carriage-member to rotate said spindle for upsetting said cradle to dislodge the finished work therefrom.

50 55 60 65 70 75 80 85 90 95 100 105 110 115 120 125

wheel, a trip-arm secured to said transverse spindle, a trip-cam with which said trip-arm engages upon the retraction of said carriage-member, spring means engaged with said first mentioned spindle to return the same to normal position, and stop means for determining the normal position of said spindle and its cradle.

15. In a machine of the kind described, a bed-frame, a pair of rotatable abrading wheels having their operative faces mutually opposed, yieldable means normally holding said opposed wheels in working position, means for automatically separating the opposed wheels for the insertion of work therebetween, a reciprocable carriage-member, guide-means projecting laterally from said bed-frame for slidably supporting said carriage-member, means for reciprocating said carriage-member on said guide means in timed relation to the separating movement of said abrading wheels, and a supporting cradle carried by said carriage-member for introducing the work between and in operative relation to said abrading wheels.

16. In a machine of the kind described, a bed-frame, a pair of rotatable abrading wheels having their operative faces mutually opposed, yieldable means normally holding said opposed wheels in working position, means for automatically separating the opposed wheels for the insertion of work therebetween, a reciprocable carriage-member, guide-means projecting laterally from said bed-frame for slidably supporting said carriage-member, means for reciprocating said carriage-member on said guide means in timed relation to the separating movement of said abrading wheels, a spindle journaled in said carriage-member, a work supporting cradle secured to the forward end of said spindle, and means operating upon the retraction of said carriage-member to rotate said spindle for upsetting said cradle to dislodge the finished work therefrom.

17. In a machine of the kind described, a bed-frame, a pair of rotatable abrading wheels having their operative faces mutually opposed, means for automatically separating the opposed faces of said abrading wheels for the insertion of work therebetween, a reciprocable carriage-member, guide-means projecting laterally from said bed-frame for slidably supporting said carriage-member, means for reciprocating said carriage-member on said guide means in timed relation to the separating movement of said abrading wheels, a spindle journaled in said carriage-member, a work supporting cradle secured to the forward end of said spindle, and means operating upon the retraction of said carriage-member to rotate said spindle for upsetting said cradle to dis-

lodge the finished work therefrom, comprising a transverse spindle journaled in said carriage-member having a drum mounted thereon, a wheel on said first mentioned spindle a pull-strap anchored upon said drum and having its opposite end secured to said wheel, a trip-arm secured to said transverse spindle, a trip-cam with which said trip-arm engages upon the retraction of said carriage-member, spring means engaged with said first mentioned spindle to return

the same to normal position, and stop means for determining the normal position of said spindle and its cradle.

In testimony, that I claim the invention 15 set forth above I have hereunto set my hand this 12th day of September, 1918.

CARL H. ROTH.
